Primary Examiner — Sheryl Lane*Assistant Examiner* — Aula Soroush(74) *Attorney, Agent, or Firm* — Scott D. Barnett; Honigman LLP(57) **CLAIM**

The ornamental design for a mouthpiece for a nebulizer, as shown and described.

DESCRIPTION

FIG. 1 is a bottom perspective view of a mouthpiece for a nebulizer showing my new design;

FIG. 2 is a bottom plan view thereof;

FIG. 3 is a top plan view thereof;

FIG. 4 is a left-side elevation view thereof;

FIG. 5 is a right-side elevation view thereof;

FIG. 6 is a rear elevation view thereof; and,

FIG. 7 is a front elevation view thereof.

The portions of the mouthpiece for a nebulizer shown in broken lines form no part of the claimed design.
